UNITED STATES PATENT OFFICE.

MARY M. DONNELLY, OF PITTSBURG, PENNSYLVANIA.

DESIGN FOR A CORN-FORK.

SPECIFICATION forming part of Design No. 26,777, dated March 16, 1897.

Application filed November 3, 1896. Serial No. 610,986. Term of patent 7 years.

To all whom it may concern:

Be it known that I, MARY M. DONNELLY, a citizen of the United States of America, residing at Pittsburg, in the county of Allegheny and State of Pennsylvania, have invented certain new Designs in Corn-Forks, of which the following is a specification, reference being had therein to the accompanying drawing.

10 My invention relates to designs for corn-forks; and it consists in the configuration that will be more fully described hereinafter.

15 The essential features of my design are a handle, a circular disk secured thereto, and three tapering prongs of equal length arranged in a triangle and projecting from said disk.

20 The accompanying drawing represents a perspective of a handle that embodies my design.

a represents a circular disk that is perfectly flat on both sides and from the outer side of which projects the handle c. From the inner side of the disk projects the three tapering prongs b, which are of the same length and are arranged in a triangle. The handle c is round, in cross-section, and largest at its outer end.

No claim is made to triangular prongs of unequal length and arranged in a line. 30

Having thus described my invention, I claim—

The design for a corn-fork, substantially as shown and described.

In testimony whereof I affix my signature 35 in presence of two witnesses.

MARY M. DONNELLY.
